(57) **CLAIM**

The ornamental design for a wireless bone conduction earphone, as shown and described.

DESCRIPTION

FIG. 1 is a front view of the of the wireless bone conduction earphone of the present invention;

FIG. 2 is a rear view of the of the wireless bone conduction earphone of the present invention;

FIG. 3 is a left side view of the of the wireless bone conduction earphone of the present invention;

FIG. 4 is a right side view of the of the wireless bone conduction earphone of the present invention;

FIG. 5 is a top view of the of the wireless bone conduction earphone of the present invention;

FIG. 6 is a bottom view of the of the wireless bone conduction earphone of the present invention;

FIG. 7 is a front perspective view of the d of the wireless bone conduction earphone of the present invention; and,

FIG. 8 is a rear perspective view of the of the wireless bone conduction earphone of the present invention.
